SHOE SHAPER

Earl E. Shurtz, Los Angeles, Calif.

Application September 16, 1946, Serial No. 697,175

3 Claims. (Cl. 12—129.1)

1

This invention relates to shoe trees and like devices for keeping shoes in proper shape.

A principal object of the invention is to provide a shoe-shaping device which is positioned exteriorly of the shoe and operates directly upon the sole of the toe thereof and also operates on the heel, whereby to straighten the sole and thereby draw the shoe into shape.

I have discovered that the most satisfactory manner of drawing shoes into shape between service intervals is to flatten the soles by direct application of pressure thereto from outside the shoe, and I have also discovered that this function may be readily accomplished by means usable for either right or left shoes and capable of being adjusted to shoes of various sizes and various shapes of toe.

It is, therefore, also an object to provide a shoe-shaper adapted for use indiscriminately upon both right and left shoes and upon shoes of various sizes and shapes.

An incidental object is to provide a shoe shaper which is especially adapted to the drying and shaping of shoes which have become wet. This is best facilitated by an externally applied shaper, such as one whereby constant pressure is applied by cantilever action to both heel and toe.

A further object is to provide a shoe-shaper which serves to produce a desired shape approximating the original shape of the shoe and avoids all tendency to bulge the shoe upper and vamp into abnormal shapes as is commonly done by many styles of shoe trees employed by insertion into shoes.

In one form of the present invention, a plate to underlie and receive the forward portion of the shoe sole is provided with forward clamps adjustable to engage the forward extremity of the sole and exert a constant straightening pressure thereon. At the rear of the plate a heel clamp is used which extends upward and is adapted to be swung over the rear of the shoe and pressed into holding position against the inside heel portion of the sole whereby to apply constant straightening pressure downward on the shoe heel against the rear end of the plate. Preferably the clamps are spring controlled and the plate is longitudinally adjustable to accommodate shoes of several sizes and lengths.

Other objects and features of construction will become apparent to those skilled in this art upon reference to the following specification and ac-

2

companying drawing wherein one illustrative embodiment of the invention is disclosed.

In the drawing:

Fig. 1 is a longitudinal vertical section showing a shoe-shaper of this invention in operative position;

Fig. 2 is a top plan view thereof, the shoe not being indicated;

Fig. 3 is a fragmentary top plan view showing 10 one form of heel clamp folded in operative position;

Fig. 4 is a rear elevation taken from the line 4—4 of Fig. 3;

Figs. 5 and 6 are fragmentary enlargements 15 showing the heel clamp construction; and

Fig. 7 is a fragmentary elevational view showing a modified form of heel clamp.

The form of the invention illustrated in the drawings comprises a main plate 10 provided, if desired, with integral up-struck spacing elements 11 to engage the under surface of the sole of a shoe as indicated, the plate 10 being also provided with a downwardly directed integral flange 12. An extension of the main plate 20 10 is provided in the form of a heel plate 14 having a peripheral flange 15, the separate heel plate 14 being used for the purpose of adjustment of the length of the shoe shaper. The forward portions of the flange 15 are parallel and are disposed in contact with corresponding parallel portions of the flange 12, whereby to guide the adjusting movements of the two plates. Adjustment is accomplished by means of a longitudinal slot 16 in which slides an adjustment set bolt 17 whose head 18 rides on the heel plate portions at the edges of the slot. The lower end of the bolt 17 passes through an aperture in the rear end of the main plate 10 and receives a washer 19 and a thumb nut 20 40 adapted to be loosened to permit adjustment and to be tightened to maintain adjustment.

Underlying approximately the forward half of the median portion of the main plate 10, which constitutes a sole-engaging plate or sole-plate, is 45 a rather broad leaf spring 25 whose rear end is secured to the main plate 10 by bolts 26 spaced as indicated to fix such rear end for insuring spring action and preventing lateral shift at its forward end. Also underlying the forward half of the 50 main plate 10, and secured by the bolts 26, is a spring plate 28 which possesses sufficient resiliency to reinforce the leaf spring 25. Attachment of the spring plate 28 is made through a folded extension 28a by way of a connecting bight 29. 55 This plate 28 and the forward portion of the

main plate 10, have generally the shape of the forward portion of the shoe sole, except that they are symmetrical and adapted to receive either a right or a left shoe. The plate 28 has dimensions slightly less than the corresponding dimensions of the plate 10 so that it fits neatly within the peripheral flange 12, but without contact therewith whereby the leaf spring 25 is enclosed within the flange 12 and between the plates 10 and 28.

The forward end of the leaf spring 25 carries two U-shaped sole engaging clips 30 mounted by means of pivots 32, such as rivets, so that the upper arm of each clip may engage over an adjacent edge portion of the toe of the shoe sole, thereby to clamp the latter upon the main plate 10. The bights of the clips 30 move vertically in a slot 33 in the plate 10 adjacent the most forward portion of the flange 12, and swing horizontally in such slot 33 about the pivots 32 whereby to accommodate any shape of shoe toe. The pivots 32 also pass through the forward end of the spring plate 28 so that the leaf spring 25 and the plate 28 both act upon the clips 30 to exert downward straightening pressure on the toe of the sole and bind the sole against the plate 10. The limited amount of slippage of the spring 25 on the plate 28 required during vertical movements of the clips 30 is provided by a limited play of the rivets 32 in the corresponding holes in the plate 28 or the spring 25, preferably in the latter. The depth of the U-shaped clips 30 is such as to accommodate shoe soles of varying thicknesses.

By such mounting of the clips 30, the toe of a shoe sole may be inserted into the clips 30 and under their upper arms upon forcing the forward end of the plate 28 upward. Release of the plate 28 causes the end of the shoe sole to be clamped upon the main plate 10 and so held by constant downward pressure. When the shoe is removed, the upper arms of the clips engage the plate 10 at one side of the slot 33 and limit return movement of the leaf spring 25 and the spring plate 28.

The heel portion of the shoe is retained in longitudinal adjustment on the heel plate 14, in the form shown in Figs. 1 to 6, by means of heel stops 40 upturned as ears at the ends of a bracket plate 42 secured to the heel plate as by means of rivets 43. Also, the heel portion of the shoe is held in position against the heel plate 14 by means of a clamp generally indicated at 44 and movably mounted upon a rearward extension 42a of the bracket plate 42. The clamp 44 comprises a curved clamping arm 45 having at one end a presser finger 46 adapted to bear downward upon the inner heel surface of the shoe as seen in Fig. 1. The other end of the arm 45 is positioned and mounted by a pivot pin 48 between two ears 49 carried at the head of an upstanding tubular post 50 containing a coil tension spring 52. The post 50 is swiveled at its lower end in a collar 54 pivoted by a transverse pivot shaft 55 between two ears 56 integral with and upstanding from the bracket plate extension 42a. The collar 54 is mounted on the pivot shaft 55 through the medium of two ears 57 which the collar carries, the shaft 55 extending through all of the ears 56 and 57 and providing means about which to swing the post 50 in a vertical plane. An annular flange 50a on the lower end of the post 50 engages the lower edge of the collar 54 to provide a swivel bearing which is held in operative position by means of the spring 52 whose lower end is attached to the lower end of the post 50 by a retaining cross pin 75

58 over which the spring is hooked. The swivel mounting and the pivotal mounting on the shaft 55 thus provide a compound joint permitting all required movement of the post 50 both horizontally and vertically.

10 The upper end of the spring 52 is secured to the lower end of a link 60 normally disposed in an upper flared portion 62 of the tubular post 50. The upper end of the link 60 is carried on a pivot pin 64 eccentrically located forward with the respect to the pivot pin 48 on a generally circular extension 45a of the clamping arm 45. By this mounting, the spring 52 both places the arm 45 under clamping tension and yields for upward swing of the arm 45 to clear the top of the shoe at the heel.

15 The functioning of the shoe shaper herein disclosed is, in general, outlined by the foregoing description. The adjustment for length of a given shoe is made through the thumb nut 20 and adjustment bolt 17. When a shoe is being placed, the toe of the shoe sole is first engaged in the clips 30 so as to be bound down on the main plate 10 under tension of the leaf spring 25 and the spring plate 28. The shoe heel is then depressed so that the heel will fall between the heel stops 40 as illustrated in Fig. 1. While so positioning the shoe, the clamping device 44 will have been turned to one side to a position such as indicated in dotted lines at the right of Fig. 2. The clamping arm 45 will then be elevated by rotation about the pivot 48 to a position such as indicated in broken lines in Fig. 1. The next step is to swing the clamping arm 45 over the heel portion of the shoe approximately as indicated in full lines at the right of Fig. 2, and then swing it down into the full line position of Fig. 1 where it presses against the inner surface of the heel portion of the shoe whereby to force the presser finger 46 down to insure engagement of the shoe heel with the uppermost elements on the heel plate 14. Such clamping relationship is maintained by the tension of the coil spring 52, this spring also compensating for varying thicknesses of heels and inner heel elements. A shoe is removed from the shaper by reversal of the operations just described. When the shaper is idle, the clamp 44 is swung down into the position illustrated in Figs. 3 and 4 where it lies upon the heel plate 14. This movement is effected by movement about the pivot shaft 55 and by rotation of the post 50 in the swivel joint provided by the collar 54.

20 In Fig. 7, a modified form of heel clamp is shown which is simpler in construction than that of Figs. 1 to 6. It consists of a right angled bracket 75, the lower leg of which is secured to the heel plate 14 by a swiveling rivet 76. The upper end of the bracket 75 carries a pivoting rivet 78 securing thereupon a vertically swinging leaf spring 80 which acts as clamping means. Normally, the spring 80 assumes the upstanding position shown, so that its upper portion 80a, which is in the form of a crook, overhangs the heel plate 14 and the heel of any shoe thereon. The swinging extremity of the crook 80a carries an eye 82 receiving the upper end of a presser link 84 which may be in the form of a closed loop, or otherwise as desired, and will perform the function performed by the presser finger 46 of the other form of heel clamp. In the position indicated, the spring 80 is under stress, the crook 80a being forced upward from its otherwise idle position and thereby acting to bind the lower end of the presser link 84 against the rear-

most portion of the inner heel face to hold the shoe heel down against the heel plate 14. The lower extremity of the spring 80 lies sufficiently below the pivoting rivet 78 to provide the necessary leverage for maintaining the operative position of the spring 80.

In using the heel clamp of Fig. 7, the spring 80 and its crook 80a may be rotated about the swiveling rivet 76 when the presser link 84 is swung up, whereby to clear the shoe top. This clamp may be folded in a storage position, similar to that shown in Fig. 3, by swinging the spring 80 and the link 84 about the pivoting rivet 78 into a horizontal position and turning the whole clamp unit upon the swiveling rivet 76.

From the foregoing description it is evident that the sole of the shoe is drawn by external pressure, applied at heel and toe, into its original substantially flat condition against the main plate 10. The drying of wet shoes is facilitated by the spacing provided by the integral spacing elements 11 rising from the upper face of the main plate 10. When the shoe sole is thus drawn into proper position, the shoe upper is automatically drawn into the desired shape without the formation of bulges and wrinkles.

It is intended that the following claims shall cover all such modifications of the generic invention herein disclosed as may fall within their scope.

I claim as my invention:

1. A shoe shaper comprising in combination: an elongated substantially flat plate adapted to receive a shoe sole and heel thereupon, and providing a toe portion at one end and a heel portion at the other end; means at said toe portion

to engage and to retain a toe portion of a shoe sole against said toe portion of said plate, the toe engaging means comprising a plurality of elements relatively movable to accommodate toes of various shapes; spring means connecting said toe engaging elements to said plate and resiliently urging them toward said plate; and means on said heel portion to overhang the heel of a shoe and engage the inner heel surface of the shoe to press the shoe heel against said heel portion of the plate.

2. A combination as in claim 1 wherein said means to overhang the shoe heel is provided with pressure means to effect pressing of the shoe heel against said heel portion of the plate.

3. A combination as in claim 1 wherein said plate has flange means on its under side enclosing said spring means.

EARL E. SHURTZ.
